THERMIONIC VALVE AMPLIFIER CIRCUITS

William Spencer Percival, Ealing, London, England, assignor to Electric & Musical Industries Limited, Hayes, Middlesex, England, a company of Great Britain

Application December 31, 1937, Serial No. 182,651
In Great Britain January 14, 1937

9 Claims. (Cl. 179—171)

This invention relates to thermionic valve amplifier circuits and is concerned with amplifiers which are required to have a considerable stage gain, while nevertheless, providing a substantially uniform amplification within a wide range of frequency.

Thermionic valve amplifiers are known for this purpose in which two or more valves are coupled together by the elements of a low pass or band 10 pass network, the network being terminated by an impedance equal, approximately to the characteristic impedance of the network.

In British patent specification No. 475,490, a coupling is described for connecting two valves 15 together in cascade comprising three half sections of a low pass network terminated at one end in mid-shunt and at the other end with the usual series *m*-derived termination, the anode-output capacity of one valve and the grid-input capacity of the other valve each forming substantially the whole of the shunt 20 capacities of the network. It is a feature of this invention that the capacity at the unterminated end of the network, i. e., the normal input end, is given a value twice the usual mid-shunt value, 25 i. e., it is equal in capacity to a full shunt element. The two shunt capacities formed by the valve capacities are thus equal and the response of the amplifier is then substantially flat with 30 frequency almost up to the cut-off frequency of the low-pass network.

In general, the output and input capacities of the valve will not be equal. Some adjustment can be made by arranging the circuit lay-out so 35 that stray capacities, e. g., of a coupling condenser, are in parallel with either the plate or grid capacity, whichever is the smaller, in order to make the total capacities at grid and plate more nearly equal to one another. In the case 40 in which a considerable difference of capacity exists, for example, in which the capacities are in the ratio of two to one, it would not appear desirable to double the smaller capacity, since it is to be expected that addition of capacity would 45 reduce the performance that could be obtained below the optimum possible for the actual total capacity at anode and grid.

It is, therefore, the chief object of the present 50 invention to provide an improved thermionic valve circuit in which two valves having unequal anode and grid capacities are coupled together with a view to providing the maximum value of pass band times stage gain without the necessity of adding capacity to the circuit.

According to the invention a thermionic valve

circuit is provided comprising two valves having unequal anode and grid capacities and wherein the anode of one of the valves is connected to the grid of a following valve through an inductance and to a loading impedance through a further inductance, the two inductances being coupled together and constituting with the anode and grid capacities of the valves, sections of a low-pass filter network.

Preferably, the loading impedance is arranged 10 to constitute a terminating impedance of the network and is of such a magnitude that the network is substantially reflectionless. The termination is preferably of the series *m*-derived type.

In the specification of co-pending patent application Serial No. 171,678, filed October 29, 1937, a superheterodyne receiver is described in which two valves are coupled in cascade through the medium of coupled coils, forming with the output and input capacities of the valves, sections of a 20 low pass network and the present invention may, therefore, be regarded as an extension or development of the invention described in the specification of this co-pending patent application.

For the purpose of describing the invention 25 more in detail, reference will now be made to the accompanying drawing in which:

Figure 1 is a diagram of a circuit in accordance with the invention.

Figure 2 is a diagram similar to Figure 1 showing an equivalent electric circuit.

Figure 3 illustrates the equivalent network of the circuit shown in Figures 1 and 2, and

Figure 4 is a modification of the circuit shown in Figure 1.

As shown in Figure 1, the circuit comprises a screened grid valve 5, the anode of which is connected through an inductance coil 6 and condenser 7 to the grid of a further screened grid valve 8, a leak resistance 9 being provided as 40 shown. The anode of the valve 5 is connected through an inductance coil 11 to a load impedance shown on the left-hand side of the dotted line 10 which is connected to the positive terminal of a source of anode current, not shown. The two 45 coils 6 and 11 are coupled together and constitute, with the output capacity of the valve 5, which is indicated in dotted lines by a condenser, and the input capacity of the valve 8, also indicated in dotted lines, by a condenser, sections of a low- 50 pass network. The reference numeral 12 indicates the input terminals for the valve 5, whilst the output terminals from the valve 8 are indicated by the reference numeral 13. The loading impedance comprises, in the example shown, the 55

resistance 17 and a half section of the series m -derived type, formed by inductance 14, condenser 15 and inductance 16. The resistance 17 is given an impedance substantially equal to the nominal impedance of the network so that the latter is substantially reflectionless. The high tension supply terminals indicated by the reference numeral 18 are shunted by a condenser 19.

Figure 2 of the drawing illustrates an equivalent circuit to Figure 1, from which it will be seen that the effect of coupling the coils 6 and 11 is, in effect, to provide a further inductance indicated at 20 between the junction of the coils 6 and 11 and the anode of the valve 5, the magnitude of the inductance 20 corresponding to the mutual inductance between the coils 6 and 11.

The effect of the coupling will be more fully described in connection with the diagram shown in Figure 3. In this figure, the condenser at the right-hand end of the network corresponds to the input capacity of the valve 8, whilst the condenser at the middle of the network corresponds to the output capacity of the valve 5. In this figure the inductances, condensers and resistance are indicated by symbols which will be employed in the following explanation. The valve 5 is a high impedance valve of the screen grid type, and thus when an alternating voltage of fixed amplitude and varying frequency is applied to its grid, a constant amplitude alternating current will flow in its anode circuit. The voltage applied to the grid of the following valve will be that appearing across the condenser at S Fig. 3 and the variations of this voltage with frequency will be the frequency response of the amplifier stage. By the principle of reciprocity, the constant current may be considered as flowing in at S. The voltage frequency response at P will then be the frequency response of the amplifier.

Regarding S as the input point, the network is seen to comprise a series m -derived termination, one m -derived section, m having the value m_1 for this section, a prototype half-section and a further capacity of value aC . The value of the inductance and capacity of the prototype half section have the values L and C so that the capacity at S is seen to be greater than the normal mid-shunt value. For the case in which it is desired to obtain a constant input impedance the capacity at S is made double the normal mid-shunt value and consequently the input impedance at S is substantially constant nearly up to the cut-off frequency as pointed out in aforesaid specification No. 475,490. The constant current fed in at S therefore sets up a constant voltage at S at all frequencies substantially up to cut-off.

Now, with the usual capacity value C only at S instead of $2C$, the impedance Z_s of the filter looking in at S is the mid-shunt impedance, and, in accordance with well known theory, is resistive, and will be given by

$$Z_s = \frac{R}{1-x^2}$$

65 where

$$x = \frac{\omega}{\omega_0}$$

ω_0 being 2π times the cut-off frequency and given by $\omega_0 LC = 1$ and ω is the angular frequency under consideration and R the nominal impedance of the filter

$$\left(= \frac{L}{C} \right)$$

The resistive impedance at Q (midshunt) will be

$$Z_Q = \frac{R[1-(1-m_1^2)x^2]}{1-x^2}$$

Since the elements of the filter are substantially wholly reactive, the power at Q is the same as at S and the voltage V_Q at Q will therefore be related to the voltage V_s at S by the equation

$$\frac{V_s^2}{Z_s} = \frac{V_Q^2}{Z_Q} \quad 10$$

Hence

$$\frac{V_Q}{V_s} = \frac{Z_Q}{Z_s}$$

Now by the use of the capacity of value $2C$ at S and the screen grid type of valve, V_s is constant with frequency. Hence, substituting the values of the impedance Z_Q and Z_s

$$V_Q \propto \sqrt{1-(1-m_1^2)x^2} \quad 1 \quad 20$$

But from the theory of the m -derived filter

$$\frac{V_P}{V_Q} = \frac{1}{1-(1-m_1^2)x^2} \quad 2$$

$$V_P \propto \frac{1}{\sqrt{1-(1-m_1^2)x^2}} \quad 3$$

Thus for $m_1 < 1$ the response will rise with frequency. For $m_1 > 1$, which may be obtained by mutual inductance between the coils as in Figure 1, the response will fall with frequency. The capacity at P is fixed by the valve capacity and equals $2m_1C$ where C is the shunt capacity of the elementary half-section. C should be as small as possible in order that the cut-off frequency may be as large as possible for a given amplification. Hence it is necessary to have $m_1 > 1$. Considering the case in which $m_1 = \sqrt{2}$. As stated this will result in a falling characteristic which may be largely corrected by reducing (relatively) the capacity at S below the value $2C$. The impedance at S, and therefore the voltage, will not rise with frequency and it can be arranged that the response at P is substantially flat with frequency up to about 0.7 cut-off frequency while the pass-band is increased. Let the capacity here be $(1+a)C$ that is to say, the increase of capacity over the normal mid-shunt value is aC where a is between 0 and 1. The impedance at S will now be

$$\frac{R}{\sqrt{1+x^2(1-a^2)}}$$

The voltage V_s at S will, therefore, be proportional to this. Hence

$$V_s \propto \frac{1-(1-m_1^2)x^2}{1-(1-a^2)x^2}$$

Hence using Equation (2) above

$$V_P \propto \frac{1}{\sqrt{[1-(1-a^2)x^2][1-(1-m_1^2)x^2]}} \quad 60$$

or

$$\frac{1}{V_P^2} \propto 1 - (2-a^2-m_1^2)x^2 + (1-a^2)(1-m_1^2)x^4 \quad 65$$

A satisfactory characteristic is obtained by making the right-hand side of the last equation equal to unity at $x = \frac{1}{2}$, then since $m_1^2 = 2$, $a = 0.45$ and then

$$\frac{1}{V_P} = \frac{1}{\sqrt{1+0.2x^2-0.8x^4}}$$

The amplitude does not vary more than 5% up to $x = 0.7$ that is to say 0.7 of the cut-off frequency. By damping the coil 6 Fig. 1, that is to say the

coil between the anode and grid a flatter characteristic is possible. The damping provided by the actual coil resistance may be sufficient.

The ratio of capacities (p) is

$$5 \quad \frac{2m}{1+a}$$

In practice, the ratio is given and it is necessary to choose m_1 and hence a to satisfy this ratio.

10 In order to compare the performance of the present amplifier stage with that described in aforesaid specification No. 475,490 in which the capacity ratio is unity or is made unity by adding capacity to supplement the lower valve capacity, the theoretical pass-bands may be compared for the same value of anode valve capacity, e. g., $10\mu\mu\text{F}$ since this is fixed in practice. For the simple network, the pass-band and stage gain is proportional to $R\omega_0$ where $\omega_0=2\pi$ times the cut-off frequency and from filter theory

$$20 \quad R\omega_0 = \frac{1}{C_0}$$

where C_0 is the shunt capacity of the elementary half section ($5\mu\mu\text{F}$).

25 For the present amplifier circuit and the same amplifier valve, the performance is again measured by the reciprocal of the elementary half section capacity. Since $2m_1C$ which equals $10\mu\mu\text{F}$ is m_1 times the full shunt capacity the elementary capacity =

$$5 \quad \frac{5}{m_1}$$

Hence the theoretical performance of the present amplifier is better by the factor m_1 .

It is assumed in the above analysis that the anode capacity is greater than the grid capacity. If the reverse is the case the position of the valves may be reversed by the principle of reciprocity. 40 The practical circuit for this case is shown in Figure 4 of the drawing in which the elements which correspond to the equivalent elements shown in Figure 1, bear the same reference numerals, but in this figure, instead of employing a series m -derived termination as shown in Fig. 1 the termination consists of a simple resistance indicated by the reference numeral 21.

45 With the circuit of Fig. 4 which is terminated with a pure resistance there is a tendency for the response curve to show a droop in the region corresponding to frequencies about half the cut-off frequency. There is also a tendency for the curve to rise in the region corresponding to frequencies about two thirds the cut-off frequency. 50 These objectionable features can be corrected simultaneously by giving the mutual inductance M between the inductance 6 and 11 a value somewhat higher than that calculated in the manner indicated above.

55 It has also been found that in the arrangement of Fig. 4, the values of the self-inductance 6 and 11 deviate only slightly from values half and a quarter respectively of an inductance $L=R^2C_1$, in which R is the load resistance 21 as indicated above, and C_1 is the total shunt capacity, that is the sum of the plate capacity of valve 5 and the grid capacity of valve 8.

60 It has thus been found convenient to give inductances 6 and 11 values of $L/2$ and $L/4$ respectively and to alter the value of M slightly to compensate.

65 If this is done, then in the case where the highest working frequency f_w , is selected to give a deviation of not more than ± 0.2 decibel in the response curve and in which the time delay is

sufficiently nearly constant with frequency that at least ten stages of amplification can be used for television purposes for frequencies up to the working frequency, all the design data can be calculated to a close approximation from the relation

$$5 \quad \frac{M}{L} = 0.17(p-1) - 0.06(p-1)^2$$

where p is the ratio between the plate capacity of valve 5 and the grid capacity of valve 8, the value of the resistance 21 being given by

$$15 \quad R = \frac{0.34}{f\omega C_1}$$

I claim:

1. A thermionic valve circuit comprising in combination two valves having unequal anode and grid capacities respectively and wherein the anode of one of the valves is connected to the grid of a following valve through an inductance and to a loading impedance through a further inductance, the two inductances being coupled together and constituting with the anode and grid capacities of the valves sections of a low-pass filter network.

2. A thermionic valve circuit according to claim 1 in which the loading impedance is arranged to constitute a terminating impedance of the network.

3. A thermionic valve circuit comprising two valves having unequal anode and grid capacities respectively and wherein the anode of one of the valves is connected to the grid of a following valve through an inductance and to a loading impedance through a further inductance, the two inductances being coupled together and constituting with the anode and grid capacities of the valves sections of a low-pass filter network, said loading impedance being arranged to constitute a terminating impedance of the network, and the anode impedance of one valve being greater than the grid capacity of the other, and the anode of said one valve being connected between the two said inductances, the grid capacity of said other valve constituting a shunt reactance at the end of the network remote from the terminating load.

4. A thermionic valve circuit comprising two valves having unequal anode and grid capacities respectively and wherein the anode of one of the valves is connected to the grid of a following valve through an inductance and to a loading impedance through a further inductance, the two inductances being coupled together and constituting with the anode and grid capacities of the valves sections of a low-pass filter network, said loading impedance being arranged to constitute a terminating impedance of the network, the anode capacity of the one valve being less than the grid capacity of the other valve, the anode capacity of said one valve constituting a shunt reactance at the end of the network remote from the terminating load.

5. A thermionic valve circuit according to claim 4 in which the first mentioned inductance has a self inductance value of substantially

$$60 \quad \frac{L}{2}$$

and the second mentioned inductance a value of substantially

$$65 \quad \frac{L}{4}$$

70 where L is given by

$$75 \quad L = R^2 C_1$$

where R is the value of the resistance in the said terminating impedance of the network and C_1 is the sum of the respective anode and grid capacities, the mutual inductance between the two inductances being given a value M substantially determined by the expression

$$\frac{M}{L} = [0.17(p-1) - 0.06(p-1)^2]$$

10 where p is the ratio between the said grid and anode capacity, this ratio being not greater than two.

15 6. A thermionic valve circuit according to claim 4 in which the first mentioned inductance has a self inductance value of substantially

$$\frac{L}{2}$$

20 and the second mentioned inductance a value of substantially

$$\frac{L}{4}$$

where L is given by

$$L = R^2 C_1$$

25 where R is the value of the resistance in the said terminating impedance of the network and is substantially equal to

$$\frac{0.34}{f_w C_1}$$

30 and C_1 is the sum of the respective anode and grid capacities, the mutual inductance between the two inductances being given a value M substantially determined by the expression

$$35 \quad \frac{M}{L} = [0.17(p-1) - 0.06(p-1)^2]$$

where p is the ratio between the said grid and anode capacity, this ratio being no greater than two.

7. A thermionic valve circuit comprising two valves having unequal anode and grid capacities respectively and wherein the anode of one of the valves is connected to the grid of a following valve through an inductance and to a loading impedance through a further inductance, the two inductances being coupled together and constituting with the anode and grid capacities of the valves sections of a low-pass filter network, said loading impedance being arranged to constitute a substantially reflectionless terminating impedance of the network. 10 15

8. A thermionic valve circuit according to claim 7 in which the anode capacity of one valve is greater than the grid capacity of the other and wherein the anode of the said one valve is connected between the two said inductances, the grid capacity of the said other valve constituting a shunt reactance at the end of the network remote from the terminating load. 20

9. A thermionic valve circuit according to claim 7 in which the anode capacity of the one valve is less than the grid capacity of the other valve, the anode of the said one valve being connected to the grid of the other valve and to the loading impedance over one of said inductances, the other of said inductances being connected between said one inductance and the load impedance, the anode capacity of said one valve constituting a shunt reactance at the end of the network remote from the terminating load. 25 30 35
